[57] **CLAIM**

The ornamental design for a combined glider and cover therefor, as shown and described.

DESCRIPTION

FIG. 1 is a front perspective view of a combined glider and cover therefor showing my design;
FIG. 2 is a front elevational view;
FIG. 3 is a rear elevational view;
FIG. 4 is a top plan view wherein the legs have been omitted for convenience of illustration; and
FIG. 5 is an elevational view showing one of the two identical ends.
